UNITED STATES PATENT OFFICE

ISAIAH S. KELLEY, OF NEW YORK, N. Y.

SUBMARINE RESCUING DEVICE

Application filed March 13, 1929. Serial No. 346,558.

The device, the subject of this invention, is intended as a means for rescuing submarines, or for indicating the position of a submarine when submerged, and while I am fully aware that releasable buoys have been proposed for submarines, it is my intention that this device will be more than a mere indicating buoy.

Another object of the invention is to provide means that may operate with the mechanisms within the submarine, for making it possible for the submarine to rescue itself under certain conditions.

Another object of the invention, is to provide means to which lifting means may be attached, and to so arrange these last mentioned means that they will be within the submarine, and will not project therefrom, as I fully appreciate that projections from the deck or the skin of the submarine are objectionable.

Another object of my invention is to provide an indicating buoy in such a position that it will not take up desirable space, and in such a way that it may be discharged forcibly from the interior of the submarine, and will not depend entirely upon its own buoyancy for its ability to leave the submarine, as buoyant devices may, from the fouling of a line, or other untoward conditions, be prevented from functioning.

With all of these objects in view, the following is what I consider the best means of carrying out the invention, and the accompanying drawings should be referred to for a complete understanding of the specification which follows.

In the drawings:—

Fig. 1 shows a submarine submerged.

Fig. 2 shows my device in a submarine. This view is partly in section.

Fig. 3 is a sectional view of the buoy, and

Fig. 4, a sectional view on a somewhat enlarged scale of a valve.

Similar reference numerals indicate like parts in all the figures where they appear.

In Fig. 1, at 1, I show a submarine. This submarine is provided with a plurality of ports, such as are shown at 2 and 3, and it will be noted that these ports may be low down

on the side of the submarine. I prefer that they should be located at what would normally be termed the "tween deck's portion". At 4, in Fig. 1, I show a buoy, floated to the surface of the water, and out of the port 3.

The arrangement, construction and operation of the parts of my device, will best be appreciated by referring to Figs. 2 and 3. As previously stated, each of the ports 2 and 3, is provided with a cover or closure, such as that shown at 5, the cover or closure being hinged at 6, and secured by a locking means which consists of an angularly bent pipe 7, and a latch 8. The latch is free to operate in a hinge 9, which is a ball and socket. The inner end 10 of the latch is retained by a hook 11, controlled by a turn buckle, or pressure device 12. At the inner side of the lever 8, is a closure 8', for the passage through the angular member 7. The hinge 6 may be a spring hinge, if desired, but this is not in my opinion, necessary.

To open the closure 5, the turn buckle 12 is released, allowing the lever 8 to move away from the member 7, and thereupon water may enter through the member 7. Air will be discharged through the lever 8 and 10, and as the air is discharged and the water enters, equalizing the pressure, the closure 5, may open.

Within the closure 5, is a chamber 13, in which I arrange a plurality of ways 14 and 15, each supporting a plurality of rollers, as shown at 16 and 17. Between the rollers, I place the buoy 4, the details of which will be later described.

Behind the buoy, I arrange a plurality of plungers 18 and 19, each operated by a spring as shown at 20 and 21, and means such as screw threaded shafts 22 and 23 are provided for tensioning the springs 20 and 21.

Within the buoy 4, I provide a buoyancy chamber 4', separated from a second chamber 24. Within this second chamber, I arrange a reel 25 for the reception of the air pipe 26, the air pipe extending from the chamber, and being secured at a convenient point, such as that shown at 27, and continues through the back wall of the chamber 14, to be connected with an air pump 28. The air pipe 29, connected through the shaft of the reel 25, con-

tinues through the chamber 4' to a mushroom head, which is provided with a cap 30, and wave baffles 31. Brackets 32 supporting the cap 30 from the baffles, admit air to the pipe 29.

5 Within the chamber 24, I also arrange a line reel 33, to which a hand line is attached. The inner end of this line is secured to a chain 34, coiled within the chambers 13. The small chain 34 may be attached to a larger chain 35, which is also coiled within the chamber 14. This large chain 35 is secured to an eye 36, which eye is in turn, firmly and reliably secured to a part of the submarine which will 10 withstand all necessary or desirable strains.

15 At 37, I show a drain pipe which may be employed to drain water of condensation from the chamber 14.

In the operation of my device, when the 20 turn buckle 12 is released, the hook 11 may be rotated from the lever 10, and as this lever is really a part of the lever 8, this lever 8, will move away from the end of the hook member 7, so that water may enter the large 25 chamber 14, and at the same time, the closure 5 is released. The closure 5 would open, except for the outside pressure of the water, but as the pressure becomes equalized, the 30 springs 20 and 21 force the buoy 4 out of the chamber 14, and when released, the buoy will move upward to the surface, unreeling at the same time, the pipe 26, and the line 33. By 35 means of the pump 28, which should be local to my device, air may be drawn into the submarine, and if the pumping machinery of the 40 submarine is in workable condition, a sufficient amount of air may be brought in to the submarine to increase the interior pressure of the submarine, to an extent possibly sufficient to float the submarine. If this is 45 not possible, sufficient air may be brought in to increase the pressure so that bulkheads will not cave, due to the water pressure, and even if this is not possible, at least sufficient air can be brought into the submarine for prolonging life. I believe, however, after a 50 study of most of the submarine accidents, that in some instances, the submarine could re-float itself, if air could be obtained, and that in most instances, the caving of the bulkheads could be prevented, and in all instances life could be prolonged.

When the buoy has reached the surface, it 55 serves as a marker; that is, a location for the submarine, and thereafter drawing up on the hand line, will raise the small chain 34, which may serve as a guide in lowering a lifting pontoon which can be secured to the larger lifting chains 35, for the purpose of ultimately raising the pontoon.

60 The tube may be employed for introducing not only air, but food. Under no normal circumstances, will the heavy lifting chain 35 be withdrawn from the submarine, as it is 65 my purpose to provide sufficient hand line

and small chain to reach from the submarine to the surface, and under all conditions that I have studied, even the small chain will not be withdrawn, the hand line being sufficient.

70 It will of course be understood that modifications may be made within the scope of the appended claims without departing from the principle or sacrificing the advantages of this invention.

75 Any number of my devices may be employed, and they may be positioned at any convenient, or a series of convenient points in a submarine.

Having carefully and fully described my invention, what I claim and desire to secure 80 by Letters Patent is:—

1. The combination with a submarine, of a chamber, a water-tight and hinged cover, therefor, means for retaining said cover closed, a hollow hook member for allowing 85 water to pass into said chamber and an air escape from said chamber to equalize the pressure exterior thereto, said hook and said air escape means serving as a locking means for said closure.

2. The combination with a submarine, of a chamber, a water-tight cover therefor, a hollow hooked shaped means for retaining said cover closed, means for allowing water to 90 pass into said chamber and air to escape therefrom to equalize the pressure exterior thereto, said equalizing means comprising a hollow bar normally engaged with said hook shaped means and serving as a locking means for said closure.

100 3. A device of the character described, comprising a chamber, a closure therefor, closing means securing said closure closed, a buoy in said chamber, an anti-frictional device for supporting said buoy, ejecting means for said buoy comprising springs and plungers arranged between the springs and the buoy, and means for compressing said springs, and a hand line and a chain connected together and to said buoy.

105 4. A device of the character described, comprising a chamber, a closure therefor, a closing means securing said closure closed, a buoy in said chamber, an anti-frictional device for supporting said buoy, ejecting means for said buoy comprising springs and plungers, arranged between the springs and the buoy, and means for compressing said springs, and a hand line and a chain connected together and to said buoy, a heavier chain 110 permanently connected to a suitable means within said submarine, said heavier chain being adapted to receive a lifting pontoon, said heavier chain being connected to said hand line so that the hand line may guide 115 the lifting pontoon into position.

ISAIAH S. KELLEY.
